20 R.J. CROSSETT,
Inventor:
Clarence Loftus
Atty.

UNITED STATES PATENT OFFICE.

ROBERT J. CROSSETT, OF CHICAGO, ILLINOIS.

CAR DUMPER.

Application filed October 29, 1921. Serial No. 511,326.

To all whom it may concern:

Be it known that I, ROBERT J. CROSSETT, residing at Chicago, in the county of Cook and State of Illinois, have invented a certain new and useful Car Dumper, of which the following is a specification.

My invention relates to a car dumper especially adapted for use in combination with railway tracks and railway cars. It is an object of my invention to provide a new, useful and efficient device of this class which can be moved from place to place on ordinary railway tracks and so arranged that the ordinary or standard railway cars may be run on to the dumper at one end and off at the opposite end.

It is a further object to provide a car dumper whereby the material within the car may be readily and quickly dumped therefrom through the top, side or bottom of the car and discharge at one side of and away from the tracks.

It is a further object to provide a car dumper with a platform having rail portions adapted to fit over and interlock with the stationary track.

It is a further object of my invention to provide readily adjustable means for detachably securing a railway car to the platform.

The above and other features of novelty, advantages and capabilities will become apparent from the detailed description of the accompanying drawings in which I have illustrated a car dumper embodying one form of my invention, but the construction there shown will be understood as illustrative only and not as defining the limits of my invention.

Figure 1 is a side elevational view of a car dumper embodying one form of my invention, showing somewhat diagrammatically, a standard Williamson gondola railway car secured in place on the dumper preparatory to dumping the car.

Figure 2 is a transverse sectional view of the same taken substantially on the line 2-2 of Figure 1.

Figure 3 is a plan view of the dumper illustrated in Figure 1 with the car removed and a portion of the device broken away and.

Figure 4 is an enlarged detailed transverse sectional view of the same having a portion thereof broken away.

Referring to the drawings in detail, the platform 10 is preferably constructed of cast plates secured together in any suitable way, for example, as illustrated in Figs. 2 and 3, although it is perfectly obvious that sheets or other material may be used with proper reinforcements. The platform 10 is provided with grooved rails 11 on which the wheels of the railway car to be dumped travel. These rails are beveled at both ends as best shown in Fig. 1, so as to permit the convenient travel of the railway car wheels on to and off of these rails. The rails 11 are so constructed as to provide a housing having beveled or upwardly inclined walls 70 or shoulders 12 adapted to fit over and receive the permanent railway tracks 13 and thus automatically align the platform and tracks 11 with the permanent stationary tracks 13, and interlock the platform with such tracks. The platform 10 is integrally provided with outwardly extending portions 14 and 15 designed to extend considerably beyond the permanent railway tracks. The side 15 is provided with a longitudinal ball 80 end bearing 16 which is pivotally connected to the socket bearing 17 by means of the clamps 18. The socket 17 being detachably anchored to the ties of the permanent railway track in any suitable manner so as to prevent sidewise movement thereof while the car is being dumped, the side portion 15 of the platform being provided with suitable notches as best shown in Fig. 3 to receive the inner end of the clamps 18 and thus permit the platform to pivot or swing about said clamps through the ball and socket arrangement just described. While I have shown the inner portion of the platform 15 provided with a ball end and a socket connected therewith, it will be understood that I do not wish to limit myself to this arrangement, for other forms of swinging connections may be utilized with practical results.

In order to secure the railway car in place on the dumper while the car is being dumped, I have provided readily adjustable means for detachably but efficiently securing the car in place. Such means comprises a pair of rods 19 spaced apart near each side 108 of the platform and extending loosely through longitudinal slots in the platform having rounded heads 20 of sufficient size to prevent the rods being pulled through the slots. The rods 20 are screw-threaded on 110

their upper ends and are connected by means of turn buckets 21, to a second pair of rods 22 of any desired length which rods 22 are screw-threaded on their upper end and provided with suitable screw-threaded clamps 23 designed to clamp or engage the top of the railway car.

It will be noted that the slots in the platform for receiving the clamp rods 20 extend longitudinally. This is for the purpose of permitting adjustment so that such rods may be moved forwardly or backwardly in order to be positioned in direct alignment with the usual side braces or frame members of the standard gondola cars, and thus not interfere with the dumping of the material when dumping through the side of the car. The swinging end or portion 14 of the platform is provided with suitable means so that a crane may be readily and quickly connected therewith for raising the platform upwardly in order to dump the car. In this particular illustration I have shown rings 24 for this purpose, for instance, as best shown in Fig. 3, although any other suitable means may be utilized.

Assuming the parts have been assembled as heretofore described, and it is desired to use my dumper for dumping railway cars, the platform is slid along the stationary tracks to the desired place or position. The socket 17 is then anchored in place by detachably securing it to the ties or otherwise. The railway car is then run on to the tracks 11; the clamp rods are then adjusted for tightly securing the car to the platform against movement in any direction. A suitable crane is then connected to the swinging end of the platform through the rings 24 and the platform gradually raised. As the raising operation proceeds the side doors are opened, if it is a car which

dumps from the side, or the bottom doors, if the car dumps from the bottom. The material is then shot by gravity on to the platform 10 and out over the edge thereof to one side of the tracks. If desired, the platform may be raised or swung sufficiently so that the material within the car can be dumped through the top thereof.

Thus, it will be seen that I have provided a very efficient car dumper with which the entire contents of the car can be quickly and readily dumped therefrom and discharged to one side of the tracks.

Having thus described my invention, I claim:

1. In a car dumper, the combination of a platform provided with rails adapted to fit over and interlock with a railway track, a bearing adapted to be secured in place away from and at one side of said track and means for pivotally mounting said platform in said bearing.

2. In a car dumper, the combination of a platform provided with rails adapted to fit over and interlock with a railway track, a bearing adapted to be secured in place away from and at one side of said track, means for pivotally mounting said platform in said bearing, and means for detachably securing a railway car in place on said platform.

3. In a car dumper a platform having rails provided on the underside with a housing having inclined walls adapted to fit over a railway track and interlock therewith for the purpose set forth.

In witness whereof, I hereunto subscribe my name to this specification in the presence of two witnesses.

ROBERT J. CROSSETT.
